WORK DESK UNIT FOR A DESIGN ENGINEER

Warren A. Nielsen, 258 N. Wilson St.,
Pasadena, Calif. 91106

Filed May 2, 1966, Ser. No. 2,105

Term of patent 14 years

(Cl. D33—7)

FIG. 1

FIG. 2

FIGURE 1 is a front perspective view of a work desk unit for a design engineer showing my design; and

FIGURE 2 is a rear perspective view thereof.

The side of the unit not shown is a mirror image of the side shown.

The dominant features of my design reside in those portions shown in full lines on the drawing.

I claim:

The ornamental design for a work desk unit for a design engineer, as shown and described.
